UNITED STATES PATENT OFFICE.

BRADLEY DEWEY, OF CAMBRIDGE, MASSACHUSETTS, ASSIGNOR TO DEWEY AND ALMY CHEMICAL COMPANY, OF CAMBRIDGE, MASSACHUSETTS, A CORPORATION OF MASSACHUSETTS.

METHOD OF ADHESIVELY SECURING ARTICLES TOGETHER.

Application filed March 22, 1920. Serial No. 367,863.

To all whom it may concern:

Be it known that I, BRADLEY DEWEY, a citizen of the United States, residing at Cambridge, in the county of Middlesex and State of Massachusetts, have invented an Improvement in Methods of Adhesively Securing Articles Together, of which the following description, in connection with the accompanying drawings, is a specification, 10 like characters on the drawings representing like parts.

The invention to be hereinafter described relates to a method of adhesively securing photograph prints, sheet paper and other 15 articles to mountings of paper, metal and other materials.

Heretofore, considerable difficulty has been experienced in mounting photo prints. Usually the adhesive which has been employed for this purpose is paste, mucilage or glue, all of which contain a substantial 20 percentage of moisture. One of these adhesives is spread over the back of the print, and the moisture therein is absorbed by the 25 paper, thereby causing the same to expand or warp after the print has been applied to the mounting, thereby causing objectionable wrinkling or puckering of the paper. Sometimes the grain of the superimposed 30 paper will run parallel to the grain of the paper mounting, and sometimes transversely thereof. In both cases wrinkling is liable 35 to occur, and in either case when the moisture dries from the paper, the latter tends to contract, and this effect may be greater in some portions than in other portions of the paper, thereby causing irregular contracting, so that as a consequence, when the adhesive has dried and set, the paper print 40 is liable to be left in a wrinkled condition. Also, the character of certain adhesives heretofore used, has been such that it is difficult uniformly to spread the same over the 45 back of the print, and portions covered by less adhesive than others are apt to bulge away from the mounting, and especially adjacent the edges of the paper print where the drying effect is more rapid than in the body of the paper print a substantial distance within the edges thereof.

In the use of paste, mucilage or glue, care must be exercised to coat the back of the paper print completely to the edges thereof in order that the latter may not curl

up away from the mounting with disfiguring effect. In applying the adhesive coating at the edges, there is danger that an excess amount of adhesive will be applied thereto, so that when the paper print is pressed against the mounting, the adhesive 55 will squeeze beyond the edges onto the mounting and disfigure the same. Also, it is difficult, if not impossible, to remove such excess adhesive from the mounting without giving the same a soiled or unsightly appearance.

The aim and purpose of the present invention, therefore, is to provide a method whereby prints and other sheet paper articles may be quickly and readily applied to 60 mountings without the objections referred to, attending the use of adhesives heretofore employed. In carrying the invention into practical effect, a rubber containing adhesive is employed which contains little or 65 no moisture, and therefore, does not have the objectionable wrinkling effect referred to. In the use of this rubber adhesive it is unnecessary to exercise care to prevent excess adhesive from working out at the 70 edges of the print onto the mounting. This is because the rubber adhesive may be readily rubbed from the mounting, and instead of soiling the mounting the adhesive 75 has a cleaning or erasing effect due to the fact that when the rubber adhesive is rubbed it will crumble or roll up into little particles to which the dirt upon the mounting adheres, and these particles may be readily 80 brushed away.

The character of the invention may be best understood by reference to the following description of the method in connection with the accompanying drawings, wherein:

Fig. 1 is a perspective view of a mounting and an inverted print thereon, illustrating the step of applying the rubber cement to the back of the print;

Fig. 2 is a plan of the mounting with the print thereon having the adhesive coating in contact with the mounting and showing the excess adhesive on the mounting adjacent the edges of the print; and

Fig. 3 is a plan of the finished article.

In the practice of the method, any appropriate rubber adhesive may be employed. One good form of such adhesive may comprise the following ingredients,—one-third

or one-half pound high grade plantation rubber, one ounce grade F rosin, and about one gallon 70° naphtha, or other suitable solvent. This adhesive may have a viscous character so that it may be conveniently marketed in a tube container 1 (Fig. 1) to facilitate application of the adhesive to articles.

The method may be practiced in securing 10 any sheet paper article to a mounting, and in the present instance of the invention, for purposes of illustration, the method is employed to secure photograph prints to mountings which may be of paper, metals or 15 other material.

To apply the adhesive to the print 3, the latter is inverted, and desirably superposed on the mounting 5 to which it is to be secured. Then the adhesive may be squeezed 20 from the tube container onto the back of the print in sufficient amount to provide a coating 7 covering the same. This coating may be spread or distributed by means of the finger or a brush, and preferably the 25 adhesive is so applied as to extend beyond the edges of the mounting and cover portions of the mounting adjacent said edges, as indicated at 9. The character of the rubber adhesive is such that it may be readily 30 spread over the back of the mounting in the form of a thin layer or coating.

After the adhesive has been applied as described, the print is reversed, and placed on the mounting with the rubber adhesive coating in engagement therewith. The print 35 may be pressed against the mounting so as to have secure adhesive engagement therewith, and any excess adhesive may be pressed out beyond the edges of the print 40 onto the mounting without objection. Then the adhesive is allowed to stand a few moments to allow the rubber adhesive to dry.

Then any adhesive which may be on the mounting adjacent the edges of the print 45 may be rubbed therefrom by the finger or any appropriate means, and this adhesive will roll from the mounting with eraser-like effect, and leave the mounting in clean condition.

Heretofore, so far as I am aware, it has 50 been impossible satisfactorily to secure prints, labels and other sheet paper articles to tin and other metals, but by the present method employing rubber adhesive, such 55 articles may be efficiently secured to metals,

due among other things to the fact that the character of the adhesive is such that it does not contract in drying and does not contract the paper and pull the same relatively to the metal mounting.

The rubber adhesive not only constitutes efficient means for securing the sheet paper article to the mounting, but also prevents ingress of moisture to the adhesive, whereas, in the use of paste, mucilage or glue, any ingress of moisture thereto between the sheet paper article and mounting is liable to weaken the adhesive and allow portions of the sheet paper article to escape from the mounting.

The mounting may be of any desired character, and when sheet metal mountings are employed, they may be flat or curved or of other form as desired.

While the method has been described for 75 purposes of illustration in the application of photo prints to mountings therefor, it will be understood that the invention is not limited thereto.

What is claimed is:—

1. A method of securing articles of different areas together, characterized by spreading on the surface of one of the articles a thin coating of viscous rubber adhesive containing a solvent, pressing the 85 articles together with the rubber adhesive between them at normal temperature and before the solvent has evaporated, thereby to unite the articles and cause any excess rubber adhesive to creep beyond one of the 90 articles onto the other, and rubbing the excess rubber adhesive therefrom after it has dried.

2. A method of securing a sheet of material on a mount, characterized by spreading on the surface of one of them a thin coating of viscous rubber adhesive containing a solvent, pressing the sheet and mount together with the rubber adhesive between them at normal temperature and before the 100 solvent has evaporated, thereby to unite the sheet and mount and force any excess adhesive beyond the margins of the sheet onto the mount, and rubbing the excess rubber adhesive from the margins of the mount 105 after it has dried.

In testimony whereof, I have signed my name to this specification.

BRADLEY DEWEY.
